UNITED STATES PATENT OFFICE.

ITHAMAR M. JUSTICE, OF DAYTON, OHIO, ASSIGNOR TO THE C. W. RAYMOND CO., OF DAYTON, OHIO, A CORPORATION OF OHIO.

DRIER SYSTEM FOR CLAY PRODUCTS.

No. 921,255.

Specification of Letters Patent.

Patented May 11, 1909.

Application filed October 5, 1908. Serial No. 456,215.

To all whom it may concern:

Be it known that I, ITHAMAR M. JUSTICE, citizen of the United States, residing at Dayton, in the county of Montgomery and State of Ohio, have invented certain new and useful Improvements in Drier Systems for Clay Products; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to various improvements in driers or drier systems, which are used for drying clay products, such as various kinds of brick, tile, fire-proofing, etc.

20 The object of the invention in a general sense, is to provide in a drier a large cubic area for the circulation of air which is heated by radiated heat, with the result that a larger amount of clay products is dried by the consumption of a substantially less 25 amount of fuel than heretofore.

25 The essential features of the drier system D F are the independent flue connections with the furnaces at the discharge end of the drier D, and extending from the furnaces the 30 entire length of the drier to the receiving end where the flues connect with one main cross flue which leads to the stack. The admission of the entire volume of air immediately back of the furnaces from which point it fills the 35 entire tunnel and moves backward in an upward direction into the stack, thus thoroughly expels all moisture from the drying tunnel. The heat-radiating flues are entirely free from the surrounding walls of the 40 tunnel, and these flues may be either brick, in which case three sides are provided in each flue for radiating the heat to the drying tunnel above, or the flue may be constructed of metallic tubing, in which case the entire circumference of the flue gives off heat. The air 45 used for drying or carrying off the moisture or water from the bricks or clay products, is admitted through ducts arranged immediately around the furnace. There is one duct 50 on each side of each ash pit, one duct on each side of each furnace, and one duct immediately above each furnace. These ducts connect with the tunnels of the drier immediately at the rear of the furnace, at which 55 point all the air used for drying is admitted

to the tunnels and flows in full volume from that point to the discharge of the tunnels into the vapor stack. The cubic space below the tunnels and trackage system is three feet in depth, and in this space the radiating flues are placed as hereinafter more particularly described. Each track is placed in a single tunnel which communicates with the stack for carrying off the moisture, and each tunnel is operated independently of any other tunnel.

Preceding a more detailed description of the invention, reference is made to the accompanying drawings, of which—

Figure 1, is a horizontal elevation through one of the tunnels and radiating space below; parts of the drier are broken away to facilitate the illustration. This illustration shows what may be termed a direct furnace metallic radiated heat drier, in that it employs metallic tubes for radiating the heat below the tunnels or trackage system. Fig. 2, is an elevation of the charging end of the drier, a portion of which is shown in section, on the line a a of Fig. 1. Fig. 3, is an elevation of the discharging end of the drier, a portion of which is in section on the line b b of Fig. 1. Fig. 4, is a cross section through one of the tunnels and radiating tube therebelow, the section being on the line c c of Fig. 1. Fig. 5, is a cross section showing the radiating flues consisting of bricks which are entirely independent of the tunnel construction and which present three heat-radiating sides. Fig. 5*, is a longitudinal vertical sectional elevation through one of the tunnels and radiating flues as shown in Fig. 5. Fig. 6, is a horizontal sectional elevation through one of the tunnels and the lower radiating space. This view is similar to Fig. 1, but it shows the drier equipped for the use of waste heat. The drier thus shown may be termed a waste-radiated heat drier. Fig. 7, is an elevation of the drier showing the charging end thereof, and part being in section on the line a' a' of Fig. 6. Fig. 8, is a horizontal longitudinal section of a portion of the drier showing one of the tunnels and trackage system and one of the heat-radiating tunnels. This section is on the line d d of Fig. 2, and shows as before stated, a tunnel and track compartment, and a flue compartment. Fig. 9, is a sectional elevation taken vertically of the drier showing means for using either the direct furnace heat or waste heat.

In a detail description of the invention, similar reference characters indicate corresponding parts.

I will first describe my improvements in connection with the employment of direct heat radiation, or the radiation of heat taken directly from the furnace as distinct from that due to the use of waste heat or the products of combustion.

Looking at Fig. 1, 1 designates a drying tunnel; there are a number of these tunnels which are non-communicating and arranged side by side and parallel with each other, and each tunnel has its own trackage system which will hereinafter be more fully described in connection with the construction of the drier. The tracks of these tunnels enable the cars containing the green clay products of manufacture to be moved into the tunnels.

The left hand end of the structure as shown in Fig. 1, is the end in which the cars are introduced to the tunnel. The right hand end is that end at which the cars are removed after the bricks or products are dried.

2 designates a furnace. There is a furnace directly under each tunnel at the discharge end of the drier, and the heat generated therein passes through an individual brick flue 3. Each of the brick flues 3 communicates with a metallic flue in the form of sections of pipe which have suitable connection with each other and with the brick flue 3 leading from the furnace. The metallic flues 4 rest upon a suitable number of brick pillars 5 and connect at the receiving end of the drier with a brick flue 6. These heat-radiating flues so consisting of brick and metallic tubing, are arranged in each of the flue tunnels 7 which lie immediately below the drying tunnel 1. The object of arranging the brick radiating flue 6 at the entrance end of the drier, is to provide for the radiation of heat of a somewhat less temperature than that radiated from the metallic flues, it being desirable to subject the green products to a less degree of heat immediately upon their entrance to the drier. The entire surfaces of the metallic radiators 4 give out heat below the drying tunnels 1, and the air which is introduced to the flue tunnel 7 is quickly heated to a degree which affords a large percentage of heat radiation as compared with the driers commonly in use, in which there is only one side or a top of the heat-radiating flue exposed for heating the air.

The cubic space below the trackage, into which the air is introduced to the flues, is an important feature of my present improvement, as thereby a large volume of heated air is constantly subjected to the clay products within the tunnels above. The air for thus drying or carrying off the moisture from the green clay products, is admitted through a series of ducts 8 on each side of the ash pit 9 and fire box of the furnace, as well as above,

see Figs. 1 and 3. The air thus admitted flows through the tunnel or tunnels containing the bricks or green clay products and is subjected to the heat radiated from the flues as before stated, with the result that the clay products are dried within a comparatively short time. It will be seen that the heat, whether it be direct furnace heat or waste heat is prevented from coming in contact with the clay products, but instead of being admitted to the drying tunnels, it is passed into the radiating flues. The arrows in Fig. 1, indicate the direction of the passage of the hot air through the drying tunnels 1 and the gases or products of combustion through the heat-radiating flues 3 7 and 6.

Referring to Fig. 2, the heat-radiating flues communicate at the end of the drier in which the bricks are taken in, with a common cross flue 9 which discharges into the stack 10, while the drying tunnel or tunnels 1 communicate with the stack 10, both the cross tunnel 9 for the radiating flues, and the drying tunnels 1 discharge through the stack 10 as indicated by the several arrows extending through the passages. Fig. 2, as before stated, indicates the end of the drier at which the green clay products are introduced, and this end of the drier is also the end at which the tunnels as well as the radiating flues discharge to the stack 10. The brick tunnels 1 at this end of the drier, are closed by doors 11 during the operation of subjecting the bricks or clay products to the heated air. Fig. 3, as stated, is the end of the drier at which the dried bricks or clay products are discharged from the drier; this end is also the firing end of the drier.

In Fig. 4, a car 12 is shown in one of the drying tunnels immediately above one of the metallic heat-radiating flues 4. This car, contains the clay products to be dried within the tunnel from the heat radiated from the flues.

Referring to Figs. 5 and 5^a, substantially the same arrangement of drying tunnels and flue tunnels are shown, with the exception that in said figures the heat-radiating flues 13 consist of brick alone instead of metallic tube radiators. The brick flues 13 as is shown in Fig. 5, present three surfaces for the radiation of heat below the drying tunnels 1. Whether the metallic means are employed for radiating the heat or the brick flues are employed for radiating the heat for the drying tunnels, a large cubic space below the trackage for heating the air is obtained, and in either event the hot gases or products of combustion are prevented from coming in contact with the clay products. We have seen that provision is made where the drying tunnels and the heat-radiating flues connect with the vapor stack, thus providing for proper opening or outlet to carry off the products of combustion from the radiating

flues as well as the moisture from the clay products without permitting the two elements to commingle in the drying tunnels.

In Fig. 6, I have shown a waste-radiated heat drier in which the waste heat or products of combustion is discharged directly into the heat-radiating flues 4 or 13 from a cross flue 14. In this view, the heat-radiating flues extend directly from the cross flue 14 to the cross exit flue 9, said radiators being supported on a series of cross T-irons 15 or any suitable means for maintaining the radiating flues in proper position.

In the use of the drier either as a waste heat or direct heat-radiation drier, it will be seen that the radiating flues extend the entire length of the drier and connect at one end with a large brick flue through which the waste heat is forced by any suitable means, such for example, as a fan not shown. The object of this construction, is to make use of the waste gases or products of combustion from burning or cooling kilns, and permitted to pass through the drier without any of the gases coming in contact with the clay ware to be dried. Fresh air for drying purposes is used, which is heated by the waste heat radiated from the metallic tubes. The arrow in Fig. 6, indicates the passage of the fresh air through a flue 16 immediately above the flue 14 and separated therefrom by an upper wall. The products of combustion pass from the radiating tubes, and the air passes from the drying tunnels 1 in this form of construction, substantially in the manner that said elements pass from the radiating flues and the drying tunnels in the form of drier shown in Figs. 1 and 2. The arrows in Fig. 7, indicate such passages.

In Fig. 9, I show a construction of the drier which is adapted for the use of direct fired heat radiation or waste heat radiation. The use of the metallic tube radiators 4 combined with brick radiators 6 at the intake end of the drier and the brick flues 3 at the furnace end of the drier, is substantially the same as the radiating flues shown in Fig. 1. But in Fig. 9, the furnace 2 is shown for the generation of direct heat to the radiating flues, and also the large brick flue 14 is shown for the waste heat. Either the furnace 2 may be employed in this setting or arrangement of the drier, or the waste heat flue 14 may be used alternately. Communicating with each of the brick-radiating flues 3, is an up flue 17 which communicates with the large brick flue 14 which receives the waste gases or products of combustion from the burning or cooling kilns as before stated. When it is not desired to utilize the waste gases or heat in this combination drier, the large brick flue 14 may be walled up, or while the waste products of combustion are being utilized, the furnace 2 of course is not employed.

In Fig. 8, one of the drying tunnels 1 is shown with its trackage system therein which will now be described. The trackage system is a part of the drier construction, and consists of heavy T rails 18 which are used for ties; these T rails are in solid lengths equal to the width of the drier. The track rails 19 are placed on top of the tie rails and at each crossing they are rigidly held together by any suitable means. Where the tie rails pass through the walls which form the tunnels, the openings are filled with a mixture of sand and cement which firmly ties the tie rails into all the walls, thus forming a solid net work of trackage, all of which is firmly tied to the masonry and is prevented from at any time getting out of a true level position. The advantage of this construction, is that a possibility of unevenness occurring in the tracks is effectually obviated. After the tracks are laid according to the plan of construction, they remain firm and rigid in their original positions.

Throughout the construction and arrangement of my improvements as thus described, the essential features have been made apparent and briefly may be stated to comprise a construction wherein there are provided a series of independent flues connecting with the source of heat at one end and with a common cross tunnel at the other end, the flues being wholly independent of any connection with the tunnel walls so that the radiation obtained from the flues has its effect upon a large surrounding area of space into which the air is introduced back of the furnace; in other words, means for obtaining a large radiation and circulation of heated air; means for utilizing the waste heat taken from a burning or cooling kiln. Heretofore, such waste heat has been utilized by permitting it to enter the drying tunnels, but this has been injurious to the clay products owing to the sulfurous gases, which, if permitted to come in contact with the clay ware, discolor it and thereby interfere with the commercial value of the products, as well as creating other damage to the cars upon which the clay ware is conveyed to the tunnels.

I claim:

1. In a drier, a series of non-communicating drying tunnels, a corresponding series of non-communicating flue tunnels below said drying tunnels, a system of trackage between the drying tunnels and the flue tunnels, a heat-radiating flue in each of the flue tunnels, said heat-radiating flues being entirely separated from the flue tunnels in which they are located, so that suitable heating space is provided in the flue tunnels for each of the heat-radiating flues, means at one end of the tunnels for generating heat for the heat-radiating flues, means for admitting air to said flue tunnels at the heat-

120
125
130

generating end, a cross tunnel at the other end of said tunnels into which the heat-radiating flues discharge, and a stack affording an outlet for said cross tunnel, and for the drying tunnels, the drying tunnels discharging into said stack above the cross tunnel, substantially as specified.

2. In a drier, a series of non-communicating drying tunnels, a corresponding series of non-communicating flue tunnels below said drying tunnels, a system of trackage between said upper and lower tunnels, means for generating heat at one end of said tunnels, means for admitting air to said tunnels at the end at which the heat is generated, a cross tunnel communicating with the series of flue tunnels at the other end thereof, a

stack into which said cross tunnel discharges, and into which the drying tunnels discharge, a combination metallic and brick radiating flue in each of said flue tunnels, and disconnected therefrom, said radiating flues having brick portions thereof at each end and which portions communicate respectively, with the heat-radiating means at one end and the cross tunnel at the other end, substantially as specified.

In testimony whereof I affix my signature, in presence of two witnesses.

ITHAMAR M. JUSTICE.

Witnesses:
